EXPRESSION CONTROL

Application filed November 19, 1927. Serial No. 234,359.

This invention relates to mechanism used in connection with a player piano action whereby different shades of musical expression are directly reproduced in accordance with certain perforations provided on the music sheet. In the embodiment of the invention shown the degree or the shade of expression is determined by the magnitude of exhaust transmitted from the main exhausting means to the striker pneumatics of the player action and the magnitude of force transmitted is under control of certain pneumatically actuated valves and means are provided for augmenting the opening movements of certain valves in accordance with the perforations in a music sheet.

The invention will be fully apparent from the following specification when read in connection with the accompanying drawings and will be defined with particularity in the appended claims.

In the drawings, Fig. 1 is a diagram showing a conventional tracker bar, player action and exhausting means combined with my improved expression mechanism;

Fig. 2 is a vertical longitudinal section through the expression mechanism, the section being taken on the line 2—2 of Fig. 3, certain valves being shown in the position 30 they assume when the third degree of expression above initial tension is effective;

Fig. 3 is a horizontal section on line 3—3 of Fig. 2;

Fig. 4 is a similar horizontal section taken approximately on line 4—4 of Fig. 2, parts being broken away to reveal details below the normal plane of section;

Fig. 5 is a vertical cross-section on line 5—5 of Fig. 2 through the so-called initial tension or pianissimo (PP) pneumatic;

Fig. 6 is a section on staggered line 6—6 of Fig. 2 through the piano (P) pneumatic;

Fig. 7 is a section on line 7—7 of Fig. 2 through the forte pneumatic;

Fig. 8 is a diagrammatic view illustrating an alternative arrangement of certain parts.

Referring in detail to the drawings, 10 represents the usual tracker bar having a plurality of openings 12 therein, usually eighty-eight in number corresponding to the eighty-

eight notes or keys in a piano. In addition to the openings 12, at one end the tracker bar is provided with openings *a*, *b*, *c* and *d*, these being connected by ducts 1, 2, 3 and 4 with the separate expression control devices to be described.

The perforated music sheet *S* as shown is perforated at *a*¹, *b*¹, *c*¹ and *d*¹ for coaction with the tracker openings *a*, *b*, *c* and *d*. These perforations are made in the music sheet so as to make it possible to reproduce a musical composition with the expression with which it is intended to be rendered by the composer, these sheets usually being perforated from a master hand-played record.

Each of the note openings 12 in the tracker bar is connected by a suitable duct 14 with a chamber 16 in the player action element 18. There are a multiplicity of these elements 18 and they collectively form what in the art is called a player action. When air is admitted to the chamber 16 of the action a diaphragm 20 is lifted and this raises a valve 22 which permits exhaust from chamber 24 to communicate through passage 26 with a small action pneumatic 28. The collapsing of this pneumatic swings a projection 30 thereon which in turn transmits its movement to an extension 32 formed on the sticker bar 34, the upper end of which strikes the whippen 36 which is pivoted at 38. This whippen as is well known transmits the motion of the pneumatic to the hammer of the piano action which strikes the string. All of the pneumatics 28 of the player action communicate with a chamber or wind chest 24 such as shown in Fig. 1 and each wind chest 24 communicates with a main duct 40 of the player action which is connected by means of a pipe or other conduit 42 with a chamber 44 formed in the expression unit.

The expression unit indicated as a whole at *E* in Fig. 1 is connected by means of a suitable tube or conduit 46 with an exhausting device which in the case illustrated comprises bellows 48 actuated by a suitable foot-treadle 50, said bellows being connected with an equalizer bellows 52.

The magnitude of exhaust transmitted from the exhausting means 48 to the striker pneumatics of the player action is controlled

by the port area of certain valves to be hereinafter described which form component parts of the expression mechanism embodying my invention.

5 In the embodiment illustrated, I provide for four different shades of musical expression above pianissimo (PP) or normal tension.

Piano (P) or first step above initial tension tone is controlled jointly by bellows A, 10 A' and A², (Fig. 4).

Mezzo-forte tone or second step above initial tension is controlled by bellows B acting in conjunction with bellows A.

15 Forte tone or third step above initial tension is controlled by pneumatic C acting in conjunction with pneumatic A. The pneumatics B and C are connected by a bar 54 so that they move together and said pneumatics are inverted as compared with the pneumatics A and A' and the arrangement is such that a collapsing movement of either pneumatic B or C will tend to expand pneumatic A. This is brought about by means 20 of a rocking arm 56 pivoted at 58 to bracket 60, the arm being connected by a link 62, to the upper end of pneumatic C, said link being connected at its lower end by means of a link 64 with the pneumatic A. As thus 25 arranged, it is clear that when either pneumatic B or C is collapsed the pneumatic A will be expanded.

The pneumatics A, A', B and C are secured to the back wall of the expression unit 30 wind chest element indicated as a whole at W. This wind chest includes chambers 66, 68, 70, 72 and 74, the chamber 66 being connected with the aforementioned suction producing means by the conduit 46. Communication between chambers 66 and 68 is controlled by a pouch actuated valve 76 located opposite the port 78 connecting said chambers. The chambers 68 and 70 are connected by a port 80. Communication between 35 chamber 70 and 72 is controlled by a pouch actuated valve 82. Both chambers 72 and 74 are adapted to communicate with the chamber 44 which is connected by means of the conduit 42 to the player action. The ports 84 connect the chamber 72 with the chamber 44. Similarly, ports 86 and 88 connect the chamber 74 with the chamber 44. The passage of air through ports 86 and 88 is controlled by pouch actuated valves 90—92, 45 and these valves are only opened at such times that the tracker openings b and c are uncovered by the perforations b¹ and c¹ of the music sheet, as hereinafter described.

50 Bellows A' at all times is in communication with the chamber 72 through port 94. This bellows is also normally in communication with chamber 74 through port 96 but the effective area of port 96 is controlled by a flap valve 98 which comprises a substantially rectangular block having a piece of

soft leather or sheep-skin glued to one face thereof, the upper end 100 of said leather forming a pivotal support for the valve. A spring 102 serves to press the valve 98 toward its seat but the valve is normally held open 70 a slight distance by means of a stop 99 (Fig. 3) secured to the movable board 104 of the bellows, said stop engaging the extension 106 of the flap valve. The pneumatic A' is normally distended by means of a spring 108— 75 hence at all times the valve 98 is held partially opened by means of pneumatic A'. The amount of valve opening thus secured is sufficient to pass enough exhaust wind to produce the lowest or softest tones herein 80 spoken of as initial tension. To secure piano (P) expression, I provide means of augmenting the opening movement of the flap valve 98, this being effected through finger 99 by the actuation of the pneumatic A² located 85 within the pneumatic A'. The pneumatic A² is brought into play whenever the perforation a¹ of the music sheet uncovers tracker opening a. This permits atmospheric pressure flowing through duct 1 to lift pouch 90 110. This causes valve 112 to be lifted so as to shut off wind from the interior of pneumatic A' to the interior of pneumatic A² and at the same time valve 114 is lifted so as to admit atmospheric air through port 95 116 to the interior of pneumatic A², which course results in augmenting the opening movement of the flap valve 98. The chamber 111 above the pouch 110 is normally under the influence of exhaust wind which is 100 communicated through port 113 leading to the interior of the pneumatic A¹.

When piano (P) expression is transmitted to the player action, it is understood that valves 82, 90 and 92 are closed and that exhaust is transmitted from the exhausting means to the player action through a port area which is controlled by the flap valve 98. The exhaust so transmitted passes from chamber 68 through a port 118 controlled 105 by a pivoted flap valve 120 into the bellows A and through port 122 to chamber 74 thence through port 96, past flap valve 98 and out through port 94 to chamber 72 and ports 84 to chamber 44 thence by way of conduit 42 110 to the striker pneumatics of the player action.

To secure forte mezzo expression, a perforation b' in the music sheet uncovers the port b in the tracker bar. This admits atmospheric air through duct 2 which results in lifting the pouch 124. This results in lifting valve 126 and thus opens communication between chamber 128 and the interior of bellows B through port 130. The chamber 128 is connected by means of port 132 with the interior of bellows A which it will be remembered is in communication with the vacuum chamber 68. Thus the effect of opening valve 126, causes the pneumatic B 125 130

to be collapsed. This collapsing movement acting through lever 56 and links 62 and 64 results in further expanding the pneumatic A. This pneumatic carries a finger 134 which upon the expanding movement of the pneumatic increases the opening movement of the flap valve 120 thereby increasing the port area controlled by said valve. The lifting of valve 126 also opens communication from chamber 128 to chamber 91 below the pouch valve 90, the chamber 91 being connected by means of a duct 136 with a port 138 located adjacent the valve 126 as shown in Figs. 2 and 4. So long as valve 126 remains in its raised position, suction will hold the valve 90 open and permit a high degree of suction to be transmitted through the port 86 to the player action. Thus the exhaust wind may be said to be shunted around the pneumatic A'. Similarly, when the perforation *c'* in the music sheet uncovers tracker opening *c*, atmospheric pressure transmitted through the duct 3 will lift pouch 140 which in turn will lift valve 142 to the position shown in Fig. 2. This will establish communication from chamber 128 to chamber 93 located below valve 92 through duct 144. Thus the pouch will be collapsed and the valve 92 opened so as to uncover port 88. At the same time, suction from chamber 128 will be transmitted through port 146 to the interior of bellows C as indicated in Fig. 7. This will collapse bellows C and through rocking lever 56 and links 62 and 64 pneumatic A will be further expanded with the result that a greater opening of flap valve 120 will be effected. It is noted that the size of bellows C is greater than that of bellows B—hence it will be appreciated that pneumatic C will exert a greater opening movement on the valve 120 than that exerted by pneumatic B.

To secure the loudest tones, the fortissimo perforation *d'* uncovers port *d* of the tracker bar. This permits atmospheric air flowing through duct 4 to lift a pouch 148 and lift valve 150. This act cuts off communication from chamber 152 (which is connected with exhaust chamber 70 by conduit 153) to chamber 154 below the pouch 156. The chamber 154 is connected by a conduit 158 with a port 160 located above the valve 150. When the valve 150 lifts it also lifts a valve 162 located in a chamber 164 which is open to atmosphere. Thus atmospheric air flowing through port 160 and conduit 158 acts on the pouch 156 thus lifting the valve 82. This provides a direct passageway for a high degree of suction through chamber 72 and ports 84 to the conduit 42 leading to the player action. Because of this unrestricted flow, a high magnitude of suction is transmitted to the action and the loudest fortissimo tones are produced.

For convenience in manufacture and as-

sembly of parts, the wind chest, W, is provided with connections 168, 170 and 172 connected with various pneumatics usually employed in player pianos which are not shown as they form no part of the present invention.

The expression mechanism is equipped also with a spring pressed exhaust valve 174 located in a chamber 176 which is open to atmosphere. This valve is adapted to be actuated by the pouch 178 which is lifted when atmospheric air is admitted through a tube 180 upon the opening of a silencer push button 182. The opening of flap valve 174 is accompanied by a closing movement of valve 76. Thus it is seen that when the pouch 178 is lifted, suction from the main bellows is entirely cut off and the player action and expression mechanism is vented to atmosphere and is, therefore, rendered non-operative. This silencer push button is usually actuated when it is desired to suppress the playing of certain parts of a selection represented by the perforated music sheet. As soon as the silencer button is released, the playing will be resumed.

In the arrangement above described, the ducts 2 and 3 lead directly from the tracker bar ports *b* and *c* to the chamber 128. Such an arrangement operates satisfactorily in connection with music sheets in which no two expression perforations are in alignment. The arrangement is also satisfactory even though the expression perforations are in alignment provided the instrument is manually pumped. With a motor pump instrument it is desirable to provide means for preventing simultaneous actuation of the valves 126 and 142 so as to prevent transmission of too high a degree of suction to the player action. Ordinarily, the rolls or music sheets adapted for use with the instrument illustrated do not have expression perforations arranged in horizontal alignment, therefore, if proper rolls are used, the tracker ports *b* and *c* will never be simultaneously uncovered. However, users of musical instruments frequently buy their music rolls indiscriminately and certain manufacturers provide rolls in which the sheets are provided with expression perforations in horizontal alignment. To meet this situation, I may provide the alternative arrangement shown in Fig. 8 in which a valve box 184 is interposed between the tracker bar port *b* and chamber below pouch 124 (Fig. 2). The valve box 184 includes a chamber 186 containing a valve 188 which when lifted closes off communication between ports 190 and 192. Thus, it is clear that when the valve 188 is elevated even though port *b* in the tracker bar is uncovered, such uncovering of the tracker bar port by an abnormal music sheet will not be effective to lift pouch 124 and valve 126. The valve 128 is arranged to be lifted by a pouch 194 whenever the tracker port *c* is

uncovered by a perforation in the music sheet. The pouch 194 is located above the chamber 196 which communicates with a branch 3^a connected to a Y fitting 3^b interposed in the expression duct 3. Above the pouch 194 there is a vacuum chamber 198 which connects by means of a pipe 200 to a vacuum chamber 128, Fig. 2. A suitable bleed-port not shown will permit communication between chambers 196 and 198.

While I have described quite specifically the details of the embodiment of the invention illustrated, it is not to be construed that I am limited thereto since various modifications and substitution of mechanical equivalents may be made by those skilled in the art without departing from the invention as defined in the appended claims.

What I claim is:—

20 1. In combination with the striker pneumatics and exhausting means of a pneumatic musical instrument, an expression control mechanism comprising a plurality of pneumatics which are normally under exhaust, 25 valves coacting therewith and one of which is always open during normal operation, and means for augmenting the opening movements of said valves so as to vary the air rarefaction or magnitude of exhaust transmitted to said striker pneumatics.

25 2. In combination with the striker pneumatics and exhausting means of a pneumatic musical instrument, an expression control mechanism comprising a plurality of pneumatics which are normally under exhaust, 30 normally open valves coacting directly with each of said pneumatics, and supplemental means controlled by the music sheet for augmenting the opening movements of said 35 valves so as to vary the air rarefaction or 40 magnitude of exhaust transmitted to said striker pneumatics.

3. In combination with the striker pneumatics and exhausting means of a pneumatic musical instrument, an expression control mechanism comprising a plurality of pneumatics which are normally in communication with said suction producing means, a chambered wind chest between the latter means 45 and said pneumatics, valves within respective pneumatics controlling the magnitude of exhaust from the wind chest through said pneumatics, means moved by said pneumatics for actuating said valves, and means for augmenting the opening movements of said 50 valves.

4. In combination with the striker pneumatics and exhausting means of a pneumatic musical instrument, an expression control mechanism comprising a plurality of pneumatics, a wind chest having chambers formed therein, respective valves for said pneumatics controlling communication between each pneumatic and an associated chamber in said 55 wind chest, means whereby said pneumatics

actuate said valves and supplemental means arranged to operate in conjunction with said pneumatics for modifying the movement of said valves.

5. In combination with the striker pneumatics and exhausting means of a pneumatic musical instrument, an expression control mechanism including a wind chest having one chamber communicating with said exhausting means and another chamber communicating with said striker pneumatics, a pneumatic having a valve operatively connected therewith adapted to control the port area through which exhaust is transmitted from one of said chambers to the other, a supplemental pneumatic and connections whereby a collapsing movement of the supplemental pneumatic influences the opening movement of said valve.

6. In combination with the striker pneumatics and exhausting means of a pneumatic musical instrument, an expression control mechanism including a wind chest having one chamber communicating with said exhausting means and another chamber communicating with said striker pneumatics, a pneumatic having a valve operatively connected therewith adapted to control the port area through which exhaust is transmitted from one of said chambers to the other, a supplemental pneumatic and connections whereby a collapsing movement of the supplemental pneumatic influences the opening movement of said valve and a normally closed valve on the action side of the first named valve and means responsive to perforations in the music sheet for simultaneously opening said second named valve and actuating said supplemental pneumatic.

7. In combination with the striker pneumatics and exhausting means of a pneumatic musical instrument, an expression control mechanism comprising a chambered wind chest between the exhausting means and the striker pneumatics, a pneumatic having ports communicating with different chambers in said wind chest, a valve actuatable by said pneumatic for controlling the effective area of one of said ports, a plurality of supplemental pneumatics each adapted to transmit a different force, and means for transmitting the movement of any of said supplemental pneumatics to said first named pneumatic.

8. In combination with the striker pneumatics and exhausting means of a pneumatic musical instrument, an expression control mechanism comprising a chambered wind chest between the exhausting means and the striker pneumatics, a pneumatic having ports communicating with different chambers in said wind chest, a valve actuatable by said pneumatic for controlling the effective area of one of said ports, a plurality of supplemental pneumatics each adapted to transmit a different force, means for transmitting the

movement of any of said supplemental pneumatics to said first named pneumatic and means controlled by the music sheet for selectively actuating any one of said supplemental pneumatics.

9. The apparatus of claim 7 in combination with tracker controlled means arranged to render one of said supplemental pneumatics non-operative in the event that two expression control ports of the tracker are simultaneously uncovered.

In witness whereof, I have hereunto signed my name.

REINHOLD BUKOW.
